(57) CLAIM

The ornamental design for a holder for hair dryer, as shown and described.

DESCRIPTION

1. Holder for hair dryer

1.1 : Left

1.2 : Front

1.3 : Back

1.4 : Perspective view folded and exploded

The industrial design is a holder for hair dryer that allows hands-free hair drying; There are filed three standard views of the design 1.1-1.3 (left, front, back); The right side view is omitted since it is identical with the left side view; In the perspective view 1.4 the holder is folded in the upper part and partially exploded, with detached claw grip and vacuum suction-cups; The appearance of the holder as a whole is associated with a lizard, whose head is a claw grip, legs are suction-cups and tail is the housing.
